ISAAC H. MILLIKEN, OF ASPINWALL, PENNSYLVANIA, ASSIGNOR TO THE MC CONWAY & TORLEY COMPANY, OF PITTSBURGH, PENNSYLVANIA, A CORPORATION OF PENNSYLVANIA.

COUPLING-CENTERING MECHANISM.

1,214,351.

Specification of Letters Patent. Patented Jan. 30, 1917.

Application filed August 17, 1916. Serial No. 115,384.

To all whom it may concern:

Be it known that I, ISAAC H. MILLIKEN, a citizen of the United States, residing at Aspinwall, in the county of Allegheny and State of Pennsylvania, have invented certain new and useful Improvements in Coupling-Centering Mechanism; and I do hereby declare the following to be a full, clear, and exact description of the invention, such as will enable others skilled in the art to which it appertains to make and use the same.

My invention relates to that class of car couplers which are mounted on railway vehicles so as to be capable of swinging or moving laterally when the cars to which they are applied pass around curves in the track.

Generally stated, the principal object of the invention is to provide a simple and efficient mechanism enabling the trainman while standing at the side of the car to shift the coupler laterally so as to position it as may be necessary for making a coupling with the coupler of another car.

A further object of my invention is to produce a mechanism for this purpose whereby the operator by pulling upon a single lever may effect a lateral shifting of the coupler in either direction; and a still further object of my invention is to provide means for the purpose indicated that may be also employed to effect an unlocking of the coupler.

Minor objects of the invention, effected by special combinations and features of elemental construction, will hereinafter appear and be particularly pointed out in the claims.

In the drawings illustrating the preferred mode in which I contemplate applying the principle of my invention, the scope whereof is pointed out in the claims, Figure 1 is a front elevation of a laterally movable car coupler combined with devices embodying my invention. Fig. 2 is a detail view, partly in side elevation and partly in section, illustrating a portion of the mechanism shown in Fig. 1. Fig. 3 is a detail side elevation of the mechanism. Fig. 4 is a detail horizontal section of one of the pocket-forming partitions of the fulcrum member.

The coupler 1 which is illustrated in the drawings is of a well known type that is mounted upon a railway car so as to be capable of swinging or moving laterally with respect thereto. It is provided with a piv-

oted knuckle 2 and with a vertically movable lock 3 adapted to restrain outward rotation of the knuckle. The lock 3 may be actuated to perform unlocking and knuckle-opening movements by means of a rotatable lifter 4 whose outer end extends into an opening in the lower end of the lock and whose inner end is provided with pintles 5 which are supported in hook-like bearings 6 formed on a bracket 7 that is rigidly secured to the coupler. At its rear end the lock actuating member 4 is provided between its pintles with a pocket or recess 8 which is adapted to receive the upwardly extending inner ends 9 of rods or bars 10 that respectively extend in opposite directions toward the sides of the car. By rotating either of the rods 10 in the proper direction the lock actuating member 4 may be rotated upwardly to raise the lock 3 to unlocked position or to cause it to perform the extended unlocking movement required for the operation of knuckle-opening mechanism with which couplers are generally provided. The special mechanism herein illustrated for unlocking the coupler is fully described in my Patent No. 1,184,116, granted May 23, 1916. While I prefer to employ it, it is to be understood that its use is in nowise essential to my invention, and that other forms of mechanism for unlocking the coupler may be employed if desired.

In order that the trainman may shift the coupler laterally to any desired position while standing at either side of the car, it is preferred to employ two operating rods or bars 10, one extending toward one side of the car and the other toward the other side, each rod being provided with its own operating mechanism; but it will be understood that only one rod and corresponding operating mechanism may be employed. Since the devices for actuating the rods 10 are identical, only one of them has been illustrated, and but one will be described.

Movably connected to the outer end of each rod 10 is an operating lever 11 the lower end of which is suitably formed to provide a handle 12 that the trainman may grasp when actuating the mechanism. As shown in the drawings, the movable connection between the rod 10 and lever 11 is preferably a pivotal one and may be conveniently formed by fashioning the outer end of the rod with jaws 13, which receive the

lever 11 between them, a bolt 14 being passed through suitable apertures in said jaws and lever. In the operation of shifting the coupler laterally in one direction the upper end 5 of the operating lever engages and fulcrums upon a fulcrum member 15 mounted on the car, and, accordingly, to insure efficient bearing engagement of the lever and fulcrum member during such operation, the 10 upper end of the lever 11 is preferably provided with a rounded head 16 which is adapted to engage and rock upon the fulcrum member.

The upper portion of the fulcrum member 15 is provided with a plurality of forwardly extending spaced projections 17 which form walls of pockets 18 that are adapted to receive the upper end of the operating lever 11. One or another of these 20 projections or walls 17, depending upon which of the pockets 18 the upper end of the lever occupies, serves as a fulcrum or bearing for the lever to rock upon. To prevent the upper end of the lever from slipping out of the pocket 18 when the coupler is being shifted, the walls or projections 17 may be interiorly shouldered, as at 19; and to prevent the upper end of the lever from catching upon the outer edges of the walls 30 17 such outer edges are preferably sharpened or beveled, as shown at 20 in Fig. 4. As a further means for preventing the lever 11 from catching upon the outer edges of the walls of the pockets, the inner face 35 of the rounded head 16 of the lever may be formed with a tapering or conical boss or lug 21, as shown in Fig. 3.

Below the point of pivotal connection of the lever 11 and rod 10 the fulcrum member 15 is provided with another series of forwardly extending lugs or projections which are adapted to be engaged by the lower portion of the lever and to form fulcrua for the latter. These projections or 45 fulcrua, as shown in Figs. 1 and 3, are preferably formed as cylindrical bars or rods 22 between adjacent ones of which the lever is adapted to enter. By forming the projections 22 with curved faces the operation 50 of the lever when in contact therewith is somewhat facilitated.

The rods 10 are preferably supported from the car body by brackets 23 which are slotted to permit the introduction and 55 withdrawal of the rods, cotters 24 being preferably employed to maintain the rods in assembled position with respect to the brackets. The brackets, which are preferably made integral with the respective fulcrum members 15, support the operating rods or members 10 in such manner that they may turn, swing and slide freely.

When the coupler is required to be shifted from its central position laterally to 60 ward the side of the car where the operator

is standing, he grasps the handle 12 of the lever and moves it forwardly until the upper end 16 of the lever enters the middle pocket 18 of the fulcrum member. An extended movement of the lever 11, after it has thus 70 been brought into operative relation to the fulcrum member, causes a rotation of the adjacent rod 10 sufficient to unlock the coupler 1 and to effect the rotation of the knuckle 2 thereof to open position, if the 75 coupler is provided with knuckle-opening mechanism and is not at that time coupled to another coupler. With the upper end of the lever in the pocket of the fulcrum member, the operator pulls laterally upon the 80 lever which, by fulcruming upon one of the adjacent walls or fulcrua 17, thus transmits a corresponding pull to the rod 10 connected to the operating lever. The coupler is thus caused to move toward the operator. 85 Should extreme lateral movement of the coupler be desired or should the leverage obtainable when the lever 11 is in one of the pockets 18 be insufficient to permit the trainman to readily shift the coupler to the 90 required position, the coupler 1 may be moved laterally a portion of the distance, after which the upper end of the lever may be transferred to the appropriate adjacent pocket, thus affording better leverage for 95 advancing further movement of the coupler.

When the coupler is to be shifted laterally away from the operator, the handle 12 of the operating lever may, if desired, be operated as heretofore described to first unlock the coupler, after which it may be swung rearwardly and upwardly until the lower portion of the lever 11 passes between two of the fulcrum projections or bars 22; but it is to be understood that the lever 11 105 may be brought into operative relation with the fulcrum projections 22 without unlocking the coupler. With the lever held in this position the trainman by pulling laterally upon the handle 12 is enabled to push upon the adjacent rod 10, thereby causing the coupler 1 to be shifted toward the side of the car opposite that at which he is stationed. In this operation the lever 11 fulcrums upon one or another of the projections 22 in a manner similar to that already 110 described. Not only may the trainman shift the coupler laterally in either direction by pulling outwardly upon the lever 11, but he may also shift the coupler laterally in 120 either direction by pushing inwardly upon it.

In the form of lock releasing mechanism that has been chosen for purposes of illustration the opening 8 in the lock actuating member 4 is of sufficient width to allow the 125 rods 10 to be turned through the angle required to permit the levers 11 to engage the lower projections 22 on the fulcrum member either when the lock 3 is in lock-set position or when it is resting on the tail of the 130

knuckle while the knuckle is in open position.

I claim:

1. In mechanism of the character indicated, the combination with a coupler mounted on a railway car so as to be capable of moving laterally, of means for shifting said coupler laterally, said means involving a lever, and means operatively connecting said lever to said coupler, the body portions of said lever on opposite sides of the point of attachment of the lever to the means for operatively connecting said lever with the coupler being respectively adapted to fulcrum on independent fulcrum points.
2. In mechanism of the character indicated, the combination with a coupler mounted on a railway car so as to be capable of moving laterally, of means for shifting said coupler laterally, said means involving a fulcrum, a lever, and means operatively connecting said lever to the coupler, said lever being rotatable in the same direction to shift said coupler laterally in either direction.
3. In mechanism of the character indicated, the combination with a coupler mounted on a railway car so as to be capable of moving laterally, of means for shifting said coupler laterally, said means involving a lever, means operatively connecting said lever to the coupler, and a fulcrum member affording a plurality of fulcra for said lever, said fulcra being arranged in a plurality of series.
4. In mechanism of the character indicated, the combination with a coupler mounted on a railway car so as to be capable of moving laterally, of means for shifting said coupler laterally in either direction, said means involving a lever, and means affording a plurality of vertically spaced fulcra adapted to be engaged by said lever.
5. In mechanism of the character indicated, the combination with a coupler mounted on a railway car so as to be capable of moving laterally, of means for shifting said coupler laterally in either direction, said means involving a fulcrum member, a lever, and means operatively connecting said lever and coupler, said lever being rotatable in opposite directions and adapted to engage said fulcrum member by rotation in either direction.
6. In mechanism of the character indicated, the combination with a coupler mounted on a railway car so as to be capable of moving laterally, of means for shifting said coupler laterally in either direction, said means involving a lever, means operatively connecting said lever and coupler and adapted to unlock said coupler, and means affording a fulcrum for said lever, said lever being rotatable in the same direction to shift said coupler in either lateral direction.
7. In mechanism of the character indicated, the combination with a coupler mounted on a railway car so as to be capable of moving laterally, of means for shifting said coupler laterally, said means involving a lever, means operatively connecting said lever and coupler, and a fulcrum member mounted on the car and adapted to coöperate with said lever, said fulcrum member being provided with a series of projections adapted to engage one end of said lever and being also provided with a further series of projections adapted to engage said lever.
8. In mechanism of the character indicated, the combination with a coupler mounted on a railway car so as to be capable of moving laterally, of means for shifting said coupler laterally, said means involving a lever, means operatively connecting said lever and coupler, and a fulcrum member for coöoperating with said lever, said fulcrum member being provided with a projection forming a fulcrum adapted to be engaged by said lever, said projecting having a curved surface forming a bearing for said lever.
9. In mechanism of the character indicated, the combination with a coupler mounted on a railway car so as to be capable of moving laterally, of means for shifting the coupler laterally, said means involving a lever, a rod operatively connecting said lever and coupler, and a fulcrum member adapted to coöperate with said lever, said fulcrum member being provided with a series of pockets adapted to receive the upper end of said lever and being also provided with a series of projections adapted to engage said lever below its point of connection to said rod.

In testimony whereof I affix my signature.

ISAAC H. MILLIKEN.
